FOREIGN PATENT DOCUMENTS

WO 03086882 A1 10/2003

Primary Examiner — Ricky Pham(74) *Attorney, Agent, or Firm* — Hudak, Shunk & Farine Co. LPA(57) **CLAIM**

The ornamental design for a “cooking rack”, as shown and described.

DESCRIPTION

FIG. 1 is a top view of the cooking rack;
 FIG. 2 is a side view thereof;
 FIG. 3 is a bottom view thereof;
 FIG. 4 is a side view thereof, turned 90° from the view shown in FIG. 2;
 FIG. 5 is a top left side perspective view thereof;
 FIG. 6 is a top front perspective view thereof; and,
 FIG. 7 is a bottom right perspective view thereof.
